UNITED STATES PATENT OFFICE.

PETER MACCAFFRAY, OF PHILADELPHIA, PENNSYLVANIA, ASSIGNOR TO
THE E. H. GODSHALK COMPANY, OF PENNSYLVANIA.

DESIGN FOR A CURTAIN.

SPECIFICATION forming part of Design No. 32,100, dated January 9, 1900.

Application filed December 16, 1899. Serial No. 740,600. Term of patent 3½ years.

To all whom it may concern:

Be it known that I, PETER MACCAFFRAY, a citizen of the United States, residing in the city and county of Philadelphia, State of Pennsylvania, have invented and produced a new and original Design for a Curtain, of which the following is a specification, reference being had to the accompanying drawing, forming part thereof.

The leading features of my design for a curtain are, first, a border composed of a group of flowers and scrolls; next, a portion of the body composed of a bower rising from said border, and, finally, another portion of the body composed of columns of flowers and scrolls rising from said bower.

The figure represents a face view of a piece of curtain embodying my design.

In the drawing, A designates the border of the curtain, the same having a group of flowers B, scrolls C, and flowers D.

E designates the body of the curtain, the same having a bower of scrolls F, which rise from the border over the flowers D thereof, and columns G, H, and J, which rise from 25 said bower F.

The column G is composed of the flowers K, the scrolls L L', and the wreath M.

The column H is composed of the scrolls N, the wreath P, the flowers Q, and the arch of 30 scrolls R.

The column J is composed of the flowers S, the scrolls T T', and the wreath U.

Having thus described my invention, what I claim as new, and desire to secure by Letters 35 Patent, is—

The design for a curtain, substantially as shown and described.

PETER MACCAFFRAY.
